INTERNAL COMBUSTION ENGINE

George Stephen Kammer, Budapest, Hungary

Original application August 18, 1937, Serial No. 159,777. Divided and this application January 31, 1938, Serial No. 187,998. In Germany August 28, 1936

1 Claim. (Cl. 123—33)

The invention relates to internal combustion engines, more particularly of the compression ignition type, although it is not limited thereto.

The subject matter of the application is divided 5 from the application Serial No. 159,777, filed on August 18, 1937.

In compression ignition engines the fuel is usually sprayed in by means of pump pressure towards the end of the compression stroke, when 10 the temperature of the air in the working cylinder has already been compressed up to the ignition temperature of the fuel. The manufacture of engines operating on this principle requires high precision and consequently expensive workshop 15 labor, so that the cost of small engines especially is disproportionately increased.

Endeavors were made to avoid having fuel pumps working against the final compression pressure but no success was achieved in consequence of the practical difficulties involved. 20 Proposals were also made to produce the fuel and air mixture in a separate device outside the engine and then to introduce it into the engine and there mix it with compressed air, but these proposals did not lead to the desired result.

According to the invention the fuel and air mixture is produced in the engine itself, namely in a mixing space or chamber arranged separately from the working space. The outlet pipe of the 25 fuel pump or the carburetter jet terminates in this separate chamber. During the spraying in of the quantity of fuel required for each working stroke the pressure of the air located in the mixing chamber is lower than the final compression 30 pressure. It may for instance be equal to atmospheric or only exceed the same slightly. Also the temperature of the air in this chamber is below the ignition temperature of the fuel. Consequently in the introduction of the fuel only a 35 slight excess pressure has to be overcome. As soon as the final compression pressure is reached, communication is established between the working cylinder space and the mixing chamber so that the high temperature air compressed by the 40 working piston flows from the former into the mixing chamber. The pressure is equalised between the two spaces and the fuel and air mixture ignites. Finally the gases are pushed out of the mixing chamber into the working cylinder.

45 The connection between mixing chamber and working cylinder is made in the form of one or more ports or passages which are opened at certain times by a controlled member. The passing over of the contents of the mixing chamber into the working cylinder is also carried out by actua-

tion at certain times of a controlled member such as a piston which as it moves forward, reduces the volume of the mixing chamber practically to zero.

The two controlled members are combined by 5 constructing the member producing the connection in the form of a valve or slider rigidly connected to the piston effecting the volume variation of the mixing chamber, e. g. in the form of a tubular valve provided with one or more ports. 10 This control member is combined with the fuel pump so that its movement represents at the same time the stroke of the pump. To this end the cylinder space of the fuel pump is formed as a hollow in the rod actuating the control member and by arranging for the pump piston to be 15 stationary.

A fuel and air mixture poor in air is produced in the mixing space which requires the addition 20 of more air for ignition. The fuel, however, has a tendency to separate out from mixtures so poor in air or rich in fuel, particularly when the volume is reduced. The volume of the mixing chamber and the quantity and pressure of the air contained in it when the fuel is sprayed in 25 are therefore given such values that no separation of fuel from the gas mixture takes place even at full load, i. e. at the largest fuel consumption; as a precaution the temperature of the mixture is increased by supplying heat.

30 Advantageously the mixing chamber obtains its air filling from the working cylinder during or after scavenging.

When the air is introduced into the mixing chamber and when the contents of the mixing 35 chamber are introduced into the working cylinder, the flow is in directions deviating from the radial in order to produce a whirling movement and make the mixture more effective.

The drawing illustrates by way of example 40 several constructional forms of an engine according to the invention.

Figures 1 and 2 are sections of two different forms taken through the axis of the working cylinder with the piston at the upper dead center.

45 Figure 3 is a transverse section of the form shown in Figure 1.

Figure 4 shows a modified detail of the structure illustrated in Figure 2.

The method of operation of the constructional 50 forms shown in Figures 1 and 2 will be described with reference to a two-stroke cycle engine with self ignition while Figure 4 is directed to a modification wherein ignition is brought about by means of an electric spark.

In the arrangement shown in Figures 1 and 2 when the working piston 1 is in the neighborhood of its lower dead centre it uncovers the usual admission and exhaust ports (not shown) located 5 near the lower limit of travel of the piston, and through them the working cylinder is scavenged with fresh air in the usual way. At the same time an auxiliary piston 2 is shifted from its upper limiting position downwards, so that a mixing chamber 3 above the piston increases in volume, the pressure therein diminishes and air flows into the chamber 3 through a port 5 in a control member constructed as a tubular valve extension of the auxiliary piston 2. As may be 10 seen from Figure 3, the axes of the passage 4 and the port 5 are set away from the radial direction of the cylindrical chamber 3, so that the air entering the chamber 3 is set into a whirling movement.

15 A hollow space 10 is provided in the rod 6 of the auxiliary piston to act as the cylinder of a fuel pump. The cylinder 10 contains a piston 7 which remains stationary even during the movement of the rod 6. The upward tubular projection of the auxiliary piston 2 as it shifts downwards closes the passage 4 and at the same time the piston 7 enters the space 10, which has been 20 filled with fuel entering through the pipe 8, and the apertures 9 in the rod 6, and presses the charge of fuel through a passage 11 into a jet 22. The fuel atomised by the jet then passes into the space 3. The passage 11 is closed by a spring loaded non-return needle valve (not shown) 25 opening towards the chamber 3.

30 As the working piston 1 moves upwards and closes the exhaust and admission ports in the usual way, it compresses the air in the cylinder. During this process the auxiliary piston 2 reaches its lower limit of travel, so that the spraying in 35 of fuel comes to an end. Thereupon the piston 2 commences its upward travel. The mixture located in the chamber 3 can have heat imparted to it through the walls by suitable construction of the engine parts bounding the chamber 3, ad- 40 vantageously also by cooling the same to a less degree than usual, so that no fuel separation occurs even during the compression. When the final compression pressure is reached in the working cylinder, the port 5 arrives at the level of the 45 axis of the passage 4, the compressed hot air flows into the chamber 3, the pressure is equalised and at the same time combustion commences. In consequence of the combustion the pressure rises in the chamber 3 and consequently the flow re- 50 verses in the passage 4. For the purpose of ensuring a whirling movement the axis of the passage 4 is set at an angle to the radial direction of the combustion chamber 16 (Figure 3). In the meantime the auxiliary piston 2 continues its 55 upward travel until it reaches its upper limit as shown in Figure 1, so that it pushes the partly burnt gases out of the chamber 3 through the port 5 and the passage 4 into the working cylinder. Accordingly the combustion process takes 60 place principally in the chamber 16. During the subsequent working stroke of the piston 1, as also during the scavenging of the working cylinder, the auxiliary piston 2 remains at its upper limit of travel, and at this time the volume of the 65 chamber 3 is practically zero. The auxiliary piston 2 only commences to move downwards again when the scavenging process of the working cylinder with fresh air has already taken place. From then onwards the processes are repeated in 70 the sequence already described.

75

The dimensions in the stroke direction of the stationary passage 4 and of the movable port 5 are so arranged that the communication of the working cylinder with the chamber 3 is established at the correct point of time and is retained as long as necessary.

The quantity of fuel to be introduced per working stroke in dependence on the load on the engine is regulated by displacing the piston 7 which is otherwise stationary during operation. So long as the top face 12 of the piston 7 is at the same level as the top of the apertures 9 in the rod 6 the piston 7 presses no fuel into the passage 11. Fuel is supplied only when the face 12 of the piston 7 enters the hollow 10. Any spraying in of fuel therefore only takes place during that portion of the unvaried stroke of the rod 6 which is determined by the position of the face 12. The piston 7 can be adjusted as to location to vary the fuel feed by shifting a double-armed lever 14 projecting through a slot 13 in the rod 6.

The engine shown in Figure 2 operates by the so-called whirling chamber method. In this case the auxiliary piston 17 and the control member in the form of a tubular valve take up their lower limiting position when the working piston 15 has reached its upper dead centre. With the parts in this position a port 19 in the piston 17 comes into register with the passage 18 and the compressed air flows from the working cylinder to the chamber 20, where the mixture ignites. In consequence of the pressure increase due to combustion the flow in the passage 18 is reversed. The auxiliary piston 17 remains during the working stroke of the piston 15 at its lower limit of travel and the combustion therefore takes place principally in the mixing chamber 20. The auxiliary piston 17 only reaches its upper limit of travel when the working stroke is nearly completed. In doing so it pushes the products of combustion out of the chamber 20 through the passage 21 into the working cylinder whence they are removed in the scavenging process. After this has occurred the auxiliary piston 17 again shifts downwards and draws fresh air into the chamber 20 from the working space 1 through another passage 21.

When the arrangement according to the invention is applied to four-cycle engines, the auxiliary piston draws the air out of the working cylinder during the suction stroke of the working piston.

The movement of the auxiliary piston described in the examples of construction can be attained at for instance by means of a cam.

The arrangement shown in Figure 4 is designed for use in engines constructed according to Figure 2 but wherein the structure of the air compressed in the working cylinder does not reach the ignition temperature of the fuel. Therefore, after communication is established between the working cylinder space and the mixing space, the mixture must be ignited, that is to say, by means of an electric spark, for which purpose a spark plug 23 is shown in position in the cylinder head.

I claim:

An internal combustion engine comprising a working cylinder and piston, a mixing chamber casing immediately beyond the working cylinder, a mixing chamber formed within said casing, a fuel jet terminating in said chamber, a member movable to vary the volume of the chamber and provided with a port to register in the minimum volume position with a passage communicating with the working cylinder, a rod connecting the said member to timed operating means, the rod

being hollowed to form a fuel pump cylinder communicating with the jet, means for admitting fuel to the fuel pump, a piston to cooperate with the fuel pump cylinder, and a member extending through the casing with one end cooperating with the piston to hold the latter fixed in operation,

the member being movable from beyond the casing to change the normally operative vertical position of the piston within the fuel pump cylinder.
